UNITED STATES PATENT OFFICE.

INGVALD E. SELSTAD, OF KINGSVILLE, TEXAS.

ADJUSTABLE SHELF-BRACKET.

1,114,921.

Specification of Letters Patent. Patented Oct. 27, 1914.

Application filed May 26, 1914. Serial No. 841,056.

To all whom it may concern:

Be it known that I, INGVALD E. SELSTAD, a citizen of the United States, residing at Kingsville, in the county of Kleberg, State of Texas, have invented certain new and useful Improvements in Adjustable Shelf-Brackets; and I do hereby declare the following to be a full, clear, and exact description of the invention, such as will enable others skilled in the art to which it appertains to make and use the same.

This invention relates to shelf brackets, particularly to the type of bracket which is angularly adjustable, and has for its object the provision of a novel shelf bracket which is adapted to be secured upon a ladder, table, post, or other place, and which may be angularly adjusted so as to form means for supporting articles in a horizontal position.

An important object is the provision of a bracket of this character particularly adapted to be attached to ladders for forming a suitable support for maintaining a paint pail or other article in a horizontal position, the parts of the bracket being so adjustably connected that any vertical or lateral angularity of the position of a ladder may be compensated for.

Another object is the provision of a bracket of this character, the parts of which will be rigidly connected when in their adjusted positions, whereby accidental displacement of the parts is positively prevented.

Other objects and advantages, such as simplicity, cheapness in manufacture, efficiency in service, indestructibility and the general improvement of the art will be carefully brought out in the following description and illustrated in the accompanying drawings, in which,

Figure 1 is a side elevation of my device applied to a ladder. Fig. 2 is a sectional view through one rail of the ladder, showing my device in top plan, Fig. 3 is a cross sectional view on the line 3—3 of Fig. 2, and, Fig. 4 is a detail view.

Referring more particularly to the drawing, the numeral 5 designates a substantially U-shaped member adapted to be secured preferably upon the rail 6 of a ladder and having one of its arms provided with a screw-threaded opening for the reception of a clamping screw 7 provided at one end with a swiveled plate 8 and at the other end with the usual finger engaging wings. The mem-

ber 5 is provided with an extension 10 having one face notched or corrugated for cooperation with a similarly notched or corrugated end of an arm 11 which is pivotally secured to the extension 10 by a clamping screw 12. By this construction it will be seen that when the screw 12 is loosened, the angular position of the arm 11 in relation to the member 5 may be varied, but when the clamping screw is tightened the arm 11 will be securely clamped in its adjusted position. Thus it is seen that the arm 11 provides for lateral angular adjustment.

In order to provide for revoluble adjustment, I form the free end of the arm 11 with a cylindrical projection 13 provided with longitudinally extending grooves or notches, as shown. The cylindrical projection 13 cooperates with a member 14 formed on the end of an arm 15. The member 14 is formed in two sections, one section 16 being rigid upon the arm 15 and provided with a laterally extending ear 17, and the other section 18 being hinged upon the section 16, as shown at 19, and provided with an ear 20 through which extends a clamping bolt 21 engaging the ear 17. The member 14 is adapted to be clamped upon the cylindrical extension 13 and is provided internally with grooves or notches coöoperating with the grooves or notches on the extension 13.

In order to provide for vertical angular adjustment, I employ an arm 21' pivotally connected with the free end of the arm 15 by a clamping screw 22. The opposing faces of the ends of the arms 15 and 21' are grooved or notched, whereby relative movement of these arms cannot take place until the clamping screw 22 is loosened, thereby preventing accidental movement of the parts. A platform 23 is secured upon the outer end of the arm 21' and is braced thereon by a plurality of curved fingers 24.

It will be apparent from the description and a study of the drawings that when my device is secured upon a ladder or other supporting member, the arms 11, 15 and 21' may be so adjusted in relation to each other that the platform 23 will be held absolutely horizontal regardless of the angular inclination of the ladder or other support. If desired, a suitable frame of wire or the like may be secured upon the platform 23 whereby a paint pail or other receptacle or article may be prevented from slipping off.

Although I have shown and described

my device as being applied to a ladder, it will be readily understood that it may be used for a multitude of purposes when secured in different places.

5 It will be readily understood that I reserve the right to make various changes in the form, construction, and arrangement of parts, without departing from the spirit of the invention or limiting the scope of the 10 subjoined claims.

Having thus described my invention, what I claim is:—

1. A device of the character described comprising a substantially U-shaped plate 15 adapted to be clamped upon a support, a horizontally adjustable swinging arm connected therewith, a cylindrical extension on the free end of said arm, a member surrounding said cylindrical extension and 20 revolvably adjustably clamped thereon, an arm extending from said last named member, an arm pivotally connected with the free end of said last named arm, a clamping screw for securing said ends together, and 25 a platform secured upon said last named arm, said last named arm being vertically adjustable.

2. A device of the character described, comprising a U-shaped member, a clamping

screw extending through one arm thereof 30 and adapted to engage a support, an arm pivoted upon said member by a clamping screw, the contacting faces of said member and said arm being provided with grooves, said arm being laterally adjustable, a cylindrical extension formed on the free end of said arm and provided with longitudinal grooves, a member surrounding said cylindrical extension and provided internally with longitudinal grooves coacting with the 40 grooves in said cylindrical extension, said last named member being formed of a rigid section and a hinged section releasably clamped thereon, an arm extending from said stationary section, an arm pivotally 45 connected with the free end of said last named arm, the ends of said last named arms having their contacting faces provided with grooves, a clamping screw extending through said ends, and a platform secured 50 upon the outer end of said last named arm.

In testimony whereof, I affix my signature, in the presence of two witnesses.

INGVALD E. SELSTAD.
